ADVERTISING SIGN

Gonzalo Michaus, Miami, Fla.

Application February 26, 1935, Serial No. 8,354

6 Claims. (Cl. 40—132)

This invention relates to improvements in advertising signs and more particularly to illuminated signs for interior use.

One of the objects of the present invention is to provide a simple and practical advertising sign particularly adapted for use within buildings although it is, of course, to be understood that with slight modifications, such as water-proofing or placing in water-proofed containers, it may be used outside.

A further object is to provide a sign of the above character having relatively few parts, which may be inexpensively manufactured and assembled.

15 A further object is the provision of a sign of the last above-mentioned character, capable of various adjustments and in which the parts are so positioned and arranged as to cause variation in the advertised image viewed without actually 20 changing the article.

A further object is the provision of a sign of the above general character in which mirrors are employed, together with flasher lights for the purpose of attracting attention more readily to 25 the matter to be advertised.

A further object is the provision of a compact, self-contained and portable sign which may be easily and quickly attached to any source of current for illuminating the same.

30 Other objects will be in part obvious from the annexed drawing and in part hereinafter indicated in connection therewith by the following analysis of this invention.

This invention accordingly consists in the features of construction, combination of parts and in the unique relation of the members and in the relative proportioning and disposition thereof, all as more completely outlined herein.

To enable others skilled in the art to fully comprehend the underlying features thereof that they may embody the same by the numerous modifications in structure and relation contemplated by this invention, a drawing depicting a preferred form of the invention has been annexed as part of this disclosure, and in such drawing like characters of reference denote corresponding parts throughout all of the views, in which—

Fig. 1 is a front elevational view, partly in section, showing the complete sign with certain parts illustrated in dotted lines;

Fig. 2 is a top elevational view, partly in section;

Fig. 3 is a front elevational view illustrating the 55 variations obtained by adjustments;

Fig. 4 is a detail view showing the manner in which one of the parts may be moved;

Fig. 5 is a detail view showing the manner in which one of the mirrors may be adjusted.

The present invention comprises an improvement over that type of sign shown in patent to Scott, No. 1,202,593.

Objections existing in prior constructions of this general character are overcome by the present invention, and reference is now made particularly to Figs. 1 and 2 wherein is shown a casing 10 (Fig. 2) constituting the rear of the sign and within which is mounted any suitable switch and converter mechanism enclosed in a suitable box 11 connected to any suitable source of power as by 15 means of conductor wire 12 and plug 13 (Fig. 3). Casing 10 is preferably made of stamped sheet metal and is provided at its four sides with a laterally extending flange 14 and forwardly extending rim 15. A cover member coextensive with 20 the front of the sign is indicated at 16. Hinges 17 connect the cover to the casing at one side, and a latch and lock mechanism 18 are provided at the opposite side. Thus, by releasing the latch 18, the cover may be swung clear of 25 the casing thereby to obtain access to the interior for reasons hereinafter stated.

Box 11 preferably contains a suitable flasher mechanism (not shown in detail) but of an electric circuit of that general thermostatic type 30 adapted to flash on a light at suitable predetermined intervals. I preferably employ a luminescent gas discharge tube light indicated at 20, extending entirely around the interior of the casing, shielded from the observer by means of an 35 inwardly extending border 21. Luminescent gas discharge tube 20 may be of the neon filled type and may be of any color or plurality of colors, or may comprise a plurality of tubes of different colors, connected with the flasher system and converter containing box 11 in any convenient manner as desired.

The casing 10 is provided with a mirror 22 of usual construction, that is, a sheet of glass provided with a rear mirrored surface. The front 45 of the casing, however, is provided with what is known as a translucent mirror that is, the front mirror 23 is usually made of two pieces of glass 23a and 23b, as shown in section at the extreme right of Fig. 2, between which is a thin layer of 50 mercury or silver 23c customarily used in mirrors of this kind.

It may be here noted that light 20 is positioned about the periphery of casing 10 in the angle formed by flange 14 and rim 15 between trans- 55

lucent mirror 23 and transparent mirror 22. The purpose of this arrangement is that mirror 23, when viewed from the front with light 20 extinguished, reflects an image of the person viewing the mirror. It has been discovered, however, that by placing an object 24, such as a package of cigarettes, in the plane of light 20 between the mirrors 22 and 23, when the light 20 is energized the package of cigarettes 24 or other article is well illuminated and clearly visible through mirror 23 while the reflection of the person in front of mirror 23 is completely eliminated. Thus, when the conventional thermostatic flasher contained in box 11 operates to energize light 20 at suitable predetermined intervals, object 24 will be clearly visible, the passage of light waves through mirror 23 serving to reduce and substantially eliminate the reflective power of layer 23c. Correspondingly, during the periods when light 20 is not energized, the resultant dark background serves to emphasize the reflective power of layer 23c and light waves impinging upon layer 23c from the outside reflect a well defined image of the person viewing the assembly to the outer surface of mirror 23.

It will be noted, by reference to Figs. 1 and 4, that the mirror 23 is pivotally mounted upon suitable trunnions 25 and 26, the latter being in the form of a set screw or nut 26 and, by loosening this nut, the angle of the mirror 23 with respect to the mirror 22 may be changed, whereupon any article interposed between the two mirrors has its reflection, when the light is energized, reflected back and forth between the mirrors 22 and 23 an innumerable number of times, thus giving an appearance of a pile of the articles being advertised extending indefinitely into the casing as illustrated, for example, in Fig. 3.

While this broad idea of a reflection of a reflection, and so on, is old in the patent to Scott noted above, it has been found by positioning the mirrors a distance apart substantially equal to the thickness of the article to be advertised, then the plurality of reflections of this article becomes contiguous to one another rather than spaced apart in pairs as might otherwise occur.

The mirror 22 is preferably mounted and held in place by means of adjustable set screws 27 (Fig. 2). By the interposition of washers 29 (Fig. 5) between the flange 14 and the back of the mirror 22, the relative distance between the two mirrors may be regulated at will.

The article to be advertised, illustratively a package of cigarettes, may be easily and quickly changed as and when desired. It is customary to secure the article 24 to one of the mirrors by a drop of glue or other suitable adhesive, for example, and by swinging the cover 16 clear of the casing the package may be easily and quickly torn off and a different package, such as chewing gum, or a cigar, may be substituted. The removability of the front cover 16 also provides for the convenient cleaning of the mirrors, which is highly important due to the high reflecting surfaces necessary to obtain the desired effect.

It is believed that the construction and operation of the device is clear from the above disclosure. It may be stated briefly, however, that before connecting the sign to a source of power the front cover 16 is released by latch 18, the mirror is properly polished, and the article to be advertised interposed and secured between the two mirrors 22 and 23. The angle of the mirror 23 is then adjusted as desired and the cover closed, whereupon the plug is inserted in a socket

and the current flows through the flasher and luminescent gas discharge tube 20 to illuminate the sign at regular intervals.

It has been found that this forms a highly desirable advertising means in wash-rooms where 5 mirrors are customarily placed. Most of the time the mirror 23 presents a perfect reflection of the person using the mirror, but, as stated above, at any suitable time interval, for example every ten seconds, the tube 20 is illuminated through the 10 flasher switch, thus eliminating the reflection of the person using the mirror and presenting the article advertised in colored lights. If the mirror 23 is tilted to a very slight angle, then innumerable 15 reflections are transmitted back and forth between mirrors 22 and 23, thus giving the sign box an appearance of great depth and as containing a great number of the articles to be advertised.

Without further analysis the foregoing will so 20 fully reveal the gist of this invention that others can by applying current knowledge readily adapt it for various applications without omitting certain features that from the standpoint of the prior art fairly constitute essential characteristics of the generic or specific aspects of this invention, and therefore such adaptations should and are intended to be comprehended within the meaning and range of equivalency of the following claims.

I claim:

1. In an advertising sign of the character described, in combination, a casing containing a conductor adapted to be attached to any source of current, a flasher box, a mirror in said casing, illuminating means in front of said mirror and connected with said flasher box, a shield covering said illuminating means, a second mirror positioned in front of the casing and illuminating means and providing a space therebetween for 40 the interposition of an article to be advertised, said second mirror being of the translucent type whereby as the light is turned "on" and "off" the article to be advertised may be viewed intermittently, means for adjustably supporting the 45 first mirror, and means for changing the angularity of the second mirror with respect thereto.

2. In an advertising sign of the character described, in combination, a casing having an electrical conductor and connections mounted there- 50 in, said casing having a flanged periphery near its front side, a cover hinged thereto and provided with latching means, a light surrounding and within the cover, a shield obscuring the light from an observer in front of the sign, a mirror 55 interposed between the front and back walls of the casing, a second mirror constituting the front of the casing and providing a space between the mirrors adapted to contain an article to be advertised, said front mirror being of the trans- 60 lucent type whereby as the light is turned "on" and "off" the article to be advertised may be viewed intermittently, and means for changing the angular relation of said mirrors whereby the article to be advertised is reflected back and forth 65 between the two mirrors.

3. In an advertising sign of the character described, in combination, a casing having an electrical conductor and connections mounted there- 70 in, said casing having a flanged periphery near its front side, a cover hinged thereto and provided with latching means, a light surrounding and within the cover, a shield obscuring the light from an observer in front of the sign, a mirror interposed between the front and back walls of 75

the casing, a second mirror constituting the front of the casing and providing a space between the mirrors adapted to contain an article to be advertised, said front mirror being of the translucent type whereby as the light is turned "on" and "off" the article to be advertised may be viewed intermittently, means for changing the angular relation of said mirrors whereby the article to be advertised is reflected back and forth between the two mirrors, and means for adjusting one of the mirrors towards and from the other to vary the space to accommodate articles of different thicknesses.

4. In an advertising sign of the character described, in combination, a casing having electrical connections therein, a flanged front cooperating with said casing being hinged at one side and latched at the other whereby the front may be swung clear to permit access to the interior of the casing, the front of said casing being provided with a translucent mirror, a second mirror behind the first mirror, a light between the two mirrors, and a shield protecting the observer from the direct rays of the light, said electrical connections including a flasher switch whereby the light is alternately turned "on" or "off" at intervals thereby intermittently illuminating the article to be advertised or to permit the front mirror to give normal reflection to the person using the mirror.

5. In an advertising sign of the character described, in combination, a casing having electrical connections therein, a flanged front cooper-

ating with said casing being hinged at one side and latched at the other whereby the front may be swung clear to permit access to the interior of the casing, the front of said casing being provided with a translucent mirror, a second mirror behind the first mirror, a light between the two mirrors, and a shield protecting the observer from the direct rays of the light, said electrical connections including a flasher switch whereby the light is alternately turned "on" or "off" at intervals thereby intermittently illuminating the article to be advertised or to permit the front mirror to give normal reflection to the person using the mirror, said front mirror being mounted on trunnions positioned on opposite sides whereby the angular relation of the two mirrors may be changed thereby to produce reflections of reflections of the article to be advertised.

6. In an advertising sign of the character described, in combination, a casing having a mirrored rear visible surface, a light surrounding said mirror, a second mirror spaced from the first mirror and constituting the front of the casing, said second mirror being translucent when illuminated by the light thereby to permit a view of the article to be illuminated positioned between said mirrors, flasher means for turning the light "on" and "off" at intervals, and means for changing the angular relation of one of the mirrors with respect to the other to produce a series of reflections of the article to be advertised.

GONZALO MICHAUS.
